[57] CLAIM

The ornamental design for a facsimile, as shown and described.

DESCRIPTION

FIG. 1 is a top, front and right side perspective view of a facsimile showing my new design;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof; and

FIG. 7 is a rear elevational view thereof.

The broken line showing of the telephone handset is for illustrative purposes only and forms no part of the claimed design.
